INVENTOR
Homer R Kennedy.

By Raymond L. Blakeslee

His ATTORNEY.

UNITED STATES PATENT OFFICE.

HOMER R. KENNEDY, OF LOS ANGELES, CALIFORNIA, ASSIGNOR TO GUSSIE M. KENNEDY, OF LOS ANGELES, CALIFORNIA.

FENDER RIM AND WIRED-EDGE TOOL AND THE LIKE.

1,427,300.

Specification of Letters Patent. Patented Aug. 29, 1922.

Original application filed March 4, 1920, Serial No. 363,196. Divided and this application filed February 14, 1921. Serial No. 444,700.

To all whom it may concern:

Be it known that I, HOMER R. KENNEDY, a citizen of the United States, residing at Los Angeles, in the county of Los Angeles and State of California, have invented new and useful Improvements in Fender Rim and Wired-Edge Tools and the like, of which the following is a specification.

This invention relates to improvements in fender rim and wired edge tools, and the like, and is a division of my now co-pending application for fender rim and wired edge tools, and the like, filed in the United States Patent Office March 4, 1920, Serial Number 363,196. The invention has for an object to provide a new and simple and effective means whereby a fender which has been damaged may have its various parts restored to a normal condition, such as re-folding and crimping the sheet metal edge around the wire edge of the fender rim, at the same time removing any kinks or irregularities incident to the wire, as well as re-shaping the general contour of the fender, 25 the rim or wire edge.

In practicing the invention, I provide means that may perform the above object with a great saving of time over any known method, and requiring no particular skill in 30 accomplishing the results desired.

The present invention is particularly applicable to the side pieces rims and edges of a fender and readily straightens or removes any irregularities not only in the side piece 35 but in the crimped wire edge joined therewith. Hand-peening may remove an indentation from a fender rim, but hand-peening is not successful when the wire edge has become bent, as the wire invariably kinks and 40 spoils the looks of the fender.

The invention consists in the novel and useful, expeditious, economical and efficient method in restoring a fender to a normal condition, as disclosed more in detail in the 45 drawing, all as hereinafter pointed out in claims.

In the drawing:

Figure 1 is a fragmentary, perspective view of a fender, the top surface, wired edge, and rim of which are shown as indented;

Figure 2 is a fragmentary longitudinal side view of a sheet metal tool shown as cooperating with a die and block between

which is disposed the rim of a fender, the 55 fender being shown in section;

Figure 3 is a fragmentary top plan view of the device shown in Figure 2; and,

Figure 4 is an elevation of a sheet metal tool used in practicing the invention.

Corresponding parts in all the figures are designated by the same reference characters.

Referring particularly to the drawing, A designates a sheet metal tool of which 1 is a long lever arm and 2 a short lever arm, 65 the line of demarkation between the two lever arms being a part, as 4, where a stud or pin 6 passes laterally through any one of a series of vertically disposed transverse perforations 5.

The arm 2 extends downwardly for a portion, then is spacedly returned for a distance as at 3. An end or head portion 7 of the arm 3 is enlarged and presents a surface which is arcuated both transversely and laterally, 75 with a portion as 8 provided with a semi-anular or arcuated groove, the outer edge of which as 9 is longitudinally thin along one side and sunk below the level of the top of the head portion 7. The enlarged head is 80 likewise provided with a lateral perforation or perforations 10 which may accommodate pins, bolts, and accessory objects joined to same. The end portion of the arm 1 is provided with a grip or handle means 12.

Obviously the work to be performed depends upon the length of the arm 1, and the distance 11 shown by dotted line between the head 7 and the fulcrumed point, which, in this case, would be about the stud 6. Thus 90 a change in location of the stud or pin 6 from one perforation 5 to another would tend to shorten or lengthen the lever arm 11 existing between the point of contact 8 with any cooperating object and any other object 95 such as a forming block and rim die, to be described later, mounted upon or supported by the stud 6. Likewise the thickness of any cooperating object is readily compensated for by the adjustment of the pin or stud 6, 100 allowing the tool A to work freely.

Cooperating with the sheet metal tool A is what may be termed a rim die B, shown in Figures 2 and 3, which includes a base portion 13 which is longitudinally slotted for 105 a portion, as at 14, and has a bent-up portion 15, the elbow of which as at 16 is arcuated and relieved so that the crimped wire

portion 17 of the fender rim may float within said relieved portion. As shown in Figure 3, a pressure block 18 having an aperture 19 (Fig. 2) passing laterally through same, accommodates the pin or stud 6, which in turn slides within the slotted portion 14 of the rim die B and into one of the perforations 5 of the lever arm 1. Referring both to Figures 2 and 3 in which the rim 20 of the fender is engaged between the block 18 and the die B, the block 18 presents an arcuated top surface 21 similar to the arcuated end surface of the fender edge 22. The die B having a slotted base is free to move so as to grip the rim 20 against the block 18 and press out any indentation. Referring to Figure 3 and to the dotted lines, it will be observed that an upward or downward, as well as a back and forth motion of the lever arm 1 tends to cause the rim 20 to be moved inwardly or outwardly at the will of the operator, thus straightening the rim and pressing out any indentations.

Joined with the rim die B as at 23 are laterally extending arms 24 and 25, the ends of which are curved. These arms constitute a means which is transversely formed at the upper extremity of the arm 15, for engaging a portion of the rim 20 on one surface thereof, as 26. The pressure block 18 has one of its surfaces as 27 engaging the opposite surface as 28 of the rim 20. Obviously the block 18 might be moved toward the rim 20 by simply changing the position of the stud 6 with relation to one of the perforations 5 in the sheet metal tool A.

While I have shown a two piece fender rim, yet it will be obvious that the device of the character just described will work equally satisfactorily on one piece fenders, that is to say, fenders wherein the rim edge and the top portion of the fender are of one piece. Furthermore, this device will operate on fenders which do not have a wire in their rim edge, such fenders having their rim edge rolled or folded to strengthen or stiffen the same.

It is obvious that many changes and variations and modifications may be made in the particular device as described, such as substituting a pressure screw, a cam eccentric, etc., on any kind of a handle for causing the rim die and pressure block to co-operate with the fender, also that said changes may be made in adapting the invention to varying conditions and requirements of use and service without departing from the true spirit of the invention.

Having thus disclosed my invention, I claim and desire to secure by Letters Patent:

1. A sheet metal tool comprising a lever arm having a returned end portion, a rim die and a pressure block adjustably and removably held to said lever arm and between

which rim die and pressure block a fender rim may be disposed, said rim die including two arms bent at angles, the elbow of which is relieved to accommodate a wired portion of the fender rim, one of said arms having a slot therein, whereby longitudinal adjustment of the rim die upon the lever may be effected.

2. A sheet metal tool comprising a lever arm having a returned end portion, a rim die and a pressure block adjustably and removably held to said lever arm and between which rim die and pressure block a fender rim may be disposed, said rim die including two arms bent at angles, the elbow of which is relieved to accommodate a wired portion of the fender rim, one of said arms having a slot therein, whereby longitudinal adjustment of the rim die upon the lever may be effected; there being means mounted transversely upon the opposite arm for engaging the rim.

3. A sheet metal tool comprising a lever arm having a returned end portion, a rim die and a pressure block adjustably and removably held to said lever arm and between which rim die and pressure block a fender rim may be disposed, said rim die including two arms bent at angles, the elbow of which is relieved to accommodate a wired portion of the fender rim, one of said arms having a slot therein, whereby longitudinal adjustment of the rim die upon the lever may be effected; there being means mounted transversely upon the opposite arm for engaging the rim; said pressure block including a body provided with curved work presenting faces corresponding to the curvature of the fender.

4. A sheet metal tool, comprising a lever arm, a rim die and a pressure block adjustably and removably held to said lever arm, and between which rim die and pressure block a fender rim may be disposed, said rim die including two arms bent at angles, the elbow of which is relieved to accommodate a portion of the fender rim, one of said arms having a slot therein, whereby longitudinal adjustment of the rim die upon the lever arm may be effected.

5. A sheet metal tool, comprising a lever arm, a rim die and a pressure block adjustably and removably held to said lever arm, and between which rim die and pressure block a fender rim may be disposed, said rim die including two arms bent at angles, the elbow of which is relieved to accommodate a portion of the fender rim, one of said arms having a slot therein, whereby longitudinal adjustment of the rim die upon the lever arm may be effected; said lever arm being provided with means for engaging the rim die.

6. A sheet metal tool, comprising a lever arm, a rim die and a pressure block ad-

justably held to said lever arm, and between which rim die and pressure block a fender rim may be disposed, said rim die including two arms bent at angles, there being a slot in said rim die whereby adjustment of the rim die with relation to the lever arm may be effected.

In testimony whereof, I have signed my name to this specification in the presence of two subscribing witnesses.

HOMER R. KENNEDY.
